P. KURTZ

GOLF GAME BOARD

Filed Jan. 13, 1928

INVENTOR:

PHILIP KURTZ,

BY
Wm. H. Young & Co.
ATTORNEYS.

UNITED STATES PATENT OFFICE.

PHILIP KURTZ, OF PHILADELPHIA, PENNSYLVANIA.

GOLF GAME BOARD.

Application filed January 13, 1928. Serial No. 246,427.

My invention relates to a new and useful golf game board particularly adapted for practicing golf putting, which in addition to developing the accuracy and efficiency of the players, also affords a very interesting and healthful amusement, adapted either for indoors or outdoors recreation by one or more persons, as desired.

My invention further relates to a novel golf game board of this character which when not in use can be folded to occupy a minimum space and to facilitate the packing, carrying or transportation thereof.

My invention further relates to a golf game board of a simple and durable construction and one which can be manufactured and distributed at a minimum cost.

To the above ends, my invention consists of an inclined, hinged front member, which when unfolded leads to a horizontal putting green or area, a gutter surrounding the latter, and a rear guard rail or wall surrounding the rear and sides of said putting green.

My invention further consists in providing said inclined, hinged front member with a rear pendant flange at its juncture with the horizontal putting green or area, whereby the angular or inclined relation of said front member to said putting green is properly maintained at all times regardless of the condition or unevenness of the floor or ground on which the golf game board is supported or placed.

My invention further consists of various other novel features of construction and advantage all as will be hereinafter described and pointed out in the appended claims.

For the purpose of illustrating my invention I have shown in the accompanying drawings one form thereof which is at present preferred by me, since the same has been found in practice to give satisfactory and reliable results, although it is to be understood that the same is susceptible of modification in various particulars without departing from the spirit or scope of the invention or sacrificing any of its advantages.

In the accompanying drawings.

Figure 1, represents a perspective view of a novel golf game board, embodying my invention, shown in actual use or in unfolded condition.

Figure 2, represents a perspective view of the same in folded or knock-down condition.

Figure 3, represents a section on line 3—3 Fig. 1.

Figure 4, represents on an enlarged scale, a perspective view of one of the hinge members detached.

Referring to the drawings, in which like reference characters indicate like parts, 1 designates my novel golf game board comprising the front inclined hinged member 2, the base member 3, the horizontally disposed putting green area or member 4 and the rear guard rail or wall 6. The putting green 4 is preferably composed of a single integral member which may be made of wood and suitably secured to the base 3, and is provided with the cups or depressions 5, which are numbered 1 to 9 inclusive which represent and correspond to the holes on a nine hole golf course and which are adapted to receive the putted golf balls. The number of the holes 5 may be increased or diminished according to requirements. The rear guard wall 6 is preferably made of an integral piece of sheet metal and is secured to the base 3 by the screws or similar fastening devices 7.

The putting green 4 is of a smaller area than the base 3 whereby a gutter or groove 8 is formed intermediate said putting green and the guard rail or wall 6 which is adapted to arrest the balls that miss the cups to 1 to 9, said gutter being formed of a rear portion and the side portions 9, which are closed at their front ends by the ends of the pendant flange 15 at the rear of the front inclined member 2 which is of a length equal to the length of the base 3 as will be understood from Figs. 1 and 2. The front inclined member 2 is hinged or pivotally mounted on the front ends of the guard wall 6 by means of the pivot pins 10, each of which pass through the hole 11 of the arm 12 of the hinge 13, the front transverse arm 14 of which is suitably secured as by welding to the underside of the front inclined member 2 as will be understood from Fig. 1. The front inclined member 2 is provided with the rear, pendant, right angled flange 15, already referred to, which when the golf board is in use, that is, when the front inclined member is in position shown in Fig. 1, abuts against the front edge 16 of the base 3, so as to form a continuation of the putting green 4, and to maintain the front member 2 always in the proper inclined relation with respect to the putting green 4 regardless of the condition of the floor or ground on which the device is positioned. When the device is not in use the front inclined member 2 is folded inwardly

105

110

over the putting green member 4, as seen in Fig. 2, thus making a very compact package and facilitating the packaging, carrying or storing thereof.

5 In the practical embodiment of my invention, the base member 3 can be made of wood or thin sheet metal and the putting green area 4 is preferably made of wood having the holes 5 bored or cut therein in staggered order substantially as seen in Fig. 1. The guard rail 6 and the hinged inclined member 2 are preferably made of thin sheet metal which can be cheaply stamped or pressed into the desired contour, and the hinge member 13 is 10 also preferably made of thin sheet metal as will be understood from Fig. 4, which can be readily stamped out of thin sheet metal or pressed to the desired contour. The arm 14 of the hinged member 13 is preferably welded 15 to the under side of the inclined member 2 so that the latter and the hinges are rigidly and effectively secured together as a unitary structure. The hinging of the inclined member 2 of the front of the board is so effected that 20 when said member 2 is unfolded, the pendant flange 15 will accurately abut against the front wall 16 of the board 4, as seen in Fig. 3, so that the top surfaces of the inclined member 2 and the putting green area 4 25 will form a continuation of each other when the putted golf ball is propelled towards the holes 5. The numbers as 1 to 9 inclusive can be stamped on discs inserted in the holes 5 or they can be stamped directly on the top exposed surfaces of the bottom board member 3. By prolonging the pendant flange 15 so 30 that it extends across the front ends of the side gutters 9, the balls are retained within said side gutters so that they can be readily 35 removed.

The device constructed in the manner shown is very light and portable and the board can be readily packed in a suitable cover or carton so as to be readily transported by the user.

45 It will thus be seen that I have devised a novel golf game board which can be used for practice outdoors and indoors, thus enabling golf enthusiasts to practice their game 50 the year round, regardless of weather conditions and which affords an amusing and healthful exercise. It will also be seen that I have provided a durable and inexpensive golf game board which will be within the 55 reach of all golfers and which will have a wide range of usefulness and serviceability.

I am aware that the invention may be embodied in other specific forms without departing from the spirit or essential attributes 60 thereof, and I therefore desire the present embodiment to be considered in all respects as illustrative and not restrictive, reference be-

ing had to the appended claims rather than to the foregoing description to indicate the scope of the invention.

65

Having thus described my invention, what I claim as new and desire to secure by Letters Patent is:

1. In a foldable golf game board, a putting green area having holes therein, a rear gutter therefor merging into side gutters, a guard rail surrounding said gutters, and a front inclined member hinged at its rear ends to the front ends of said guard rail.

70 2. In a foldable golf game board, a putting green area having holes therein, a rear gutter therefor merging into side gutters, a guard rail surrounding said gutters, a front inclined member hinged at its rear ends to the front ends of said guard rail, and a pendant rear flange on said hinged member abutting against the front of said putting green area, when said member is in unfolded position.

75 3. A golf game board, comprising a base portion, a guard rail surrounding the rear and sides thereof, a putting green area having holes therein and of less area than said base and supported on the latter, rear and side gutters formed on said base between the rear and side edges of said putting green area and said guard rail, and a front inclined member having its rear ends pivotally supported upon the front ends of said guard rail.

80 4. A golf game board comprising a base portion, a guard rail surrounding the rear and sides thereof, a putting green area having holes therein and of less area than said base and supported on the latter, rear and side gutters formed on said base between the rear and side edges of said putting green area and said guard rail, a front inclined member having its rear ends pivotally supported upon the front ends of said guard rail and a rear, pendant flange on said inclined member abutting against the front edge of said putting green area and forming a closure for the front ends of said side gutters when said front inclined member is in unfolded position.

85

85 5. In a foldable golf game board, a putting green area having holes therein, a rear gutter therefor merging into side gutters, a guard rail surrounding said gutters, a front inclined member and an integral hinge having a longitudinal, rearwardly extending member adapted to be pivotally secured to the front end of said guard rail and having a transverse, laterally extending member adapted to be rigidly secured to the base of said front, inclined member, hingedly to secure the latter in foldable position with respect to said base portion.
